UNITED STATES PATENT OFFICE.

JAMES O. KING, OF CLEVELAND, OHIO.

ABDOMINAL TRUSS.

Application filed February 27, 1924. Serial No. 695,561.

Among the objects of my invention are:—
 The provisions of a waterproof truss which may be worn while bathing; the provision of a ventilated pad for an abdominal truss; the provision of a pad having a foraminated face for abdominal trusses; the provision of a foraminated sheet metal pad for abdominal trusses; the provision of an all-metal, waterproof, elastic band for abdominal trusses; the provision of novel means for adjusting the tension in the waist and leg bands of abdominal trusses; the provision of novel means for adjusting the position and determining the direction of pressure of the pads of abdominal trusses; and the provision of a truss which may be worn continuously night and day without removal and without inconveniencing or annoying the wearer.

These and other objects are accomplished by the use of my invention described herein and shown in the accompanying drawings in which:

Fig. 1 is a front view of a truss upon the body of wearer;

Fig. 2 is a plan view of the truss pads showing their position upon the body;

Fig. 3 is a fragmentary plan view of one of the truss pads shown in Fig. 2 but showing the spring bands connected to the pad at different points to obtain a different direction of application of pad pressure upon the body;

Fig. 4 is a fragmentary view of a truss in which the waist band is formed in part of non-elastic webbing;

Fig. 5 is a fragmentary view of Fig. 4 taken on line V—V of Fig. 4;

Fig. 6 is a full-size, front elevation of one of my improved pads;

Fig. 7 is a vertical axial section on line VII—VII of Fig. 6;

Fig. 8 is a rear elevation of the pad shown in Figs. 6 and 7;

Fig. 9 is a vertical section on line IX—IX of Fig. 7;

Fig. 10 is a full-size view, partly in section, of one of the swivel connections;

Fig. 11 is a full-size view of one of the detachable swivel connections;

Fig. 12 is a full-size front elevation of an oblong pad;

Fig. 13 is a side elevation of the pad shown in Fig. 12;

Fig. 14 is a view of a spring-adjusting 55 swivel connection;

Fig. 15 is a fragmentary view of a truss in which the waist band is composed of two parallel spring bands.

Referring to Fig. 1 of the drawings where 60 a two pad truss is shown upon the body of the wearer, 1 represents the helical wire spring waist band of a two pad truss. The waist band encircles the waist of the wearer just above the thighs and its ends are secured, preferably adjustably, to the pads, 2, 3. A short section, 4, of the waist band joins these pads across the front of the body. This short section, 4, is secured preferably adjustably to the pads, 2 and 3. Leg 70 bands, 5 and 6, secured preferably adjustably to the pads, 2 and 3, respectively, pass down under the torso and up the back to the waist band, 1, where they are secured preferably by means of detachable swivel 75 connectors, 7, 8.

The elastic spring bands may be adjustably secured to the pads by screwing the spring convolutions through suitable holes in the pad shells as will be further described.

When only a single pad is worn, as for instance, pad, 3, upon the right side of the body, the other pad, 2, on the left side and the corresponding leg band, 5, on the left side, 85 are omitted and the waist band, 1, has both its ends connected, preferably adjustably, directly to pad, 3. The leg band, 6, is used with the right side pad, 3. It is obvious that if the left side pad, 2, were to be used 90 alone then the leg band, 6, would be dispensed with and only leg band, 5, would be used.

The form of pad which I prefer to use has its body contacting face made of foraminated sheet-metal or other waterproof material. The pad is preferably hollow and the perforations of the face extend into the hollow interior to form a ventilated face. This construction provides for the evapora- 95 100

tion of perspiration from the skin which is in contact, with the pad, the ventilation of the skin and the draining of the pad on coming out of the bath.

5 I prefer to make the elastic band 1 of my truss of helical wire spring, and for this purpose I have found that phosphor-bronze wire, about No. 20, American wire gauge, is suitable. I have also found that the 10 outside diameter of the spiral spring may be satisfactorily made about three sixteenths of an inch. The helix should be of such a pitch that the coils of the wire are slightly separated so as not to pinch the skin of the 15 wearer or otherwise annoy him.

Full size views of a pad which I have found suitable for securely holding hernia are shown on the drawings as filed with this application in the Patent Office, in Figs. 20 6, 7, 8 and 9, and full size views of a special shaped pad are shown in Figs. 12 and 13.

Referring to Figs. 6 to 9 inclusive of the drawings, the pad therein shown is preferably made of foraminated sheet-metal such 25 as aluminum, nickel or other metal which is not corroded by contact with the body. It will be understood that any other suitable foraminated material may be used. The pads may be formed in any suitable manner 30 and of any desired shape. I have found it convenient to form the pad in two parts in which the face, 9, is secured telescopically at its rim to the back, 10, of the pad. This construction is well illustrated in Fig. 7 of 35 the drawings. The perforations of the foraminated material of which the face of the pad preferably is made are shown by small dots, 11, in Figs. 6 to 9, 12 and 13. I have found that pads having their faces made of 40 perforated sheet metal are superior to imperforate faced pads because the perforations permit the escape of perspiration and ventilate the surface of the skin beneficially. In fact after wearing a pad made of foraminated, sheet aluminum for several months, 45 continuously night and day, the skin of the wearer appears to be practically normal and there is no discoloration, which is in marked contrast to the distressing condition and dis- 50 coloration of the skin which are caused by the use of imperforate pads especially those made of rubber or synthetic, waterproof compounds.

The depth of the face part 9 of the pad 55 may be made greater or less than shown in the drawings in order that the pad may exert proper pressure over the hernia and to adapt the truss to meet individual requirements. It is obvious that various forms and 60 dimensions of pads may be made following the general principles of construction illustrated and described herein.

To secure the elastic spring bands to the 65 pads, holes such as those shown at 12 in Figs. 6, 7, 9, 12 and 13 may be used. As

many of these holes may be formed as is found desirable, preferably in the back portion, 10, of the pads. The holes, 12, are made slightly larger than the diameter of the wire used for making the helical spring 70 bands. If the wire be one thirty second inch in diameter, the holes, 12, may be made about three sixty fourths inch in diameter. The end of the helical, coiled spring, as 13, is threaded through one of the holes, 12, the 75 end of the wire being preferably bent slightly outward from the helix for starting it into the hole. After the spring has been entered through the hole the end convolution of the wire may be bent into a ring as 80 shown at 13^a Fig. 7, in order to prevent the end of the spring from being unintentionally detached from the pad. By making the face, 9, and back, 10, of the pad separable, the springs may be secured in holes, 12, before the parts, 9 and 10, are secured together. 85

Suitable drain holes, 12^a, may be provided for the escape of bath water from the pad.

Swivels or turn-buckles such as are shown at 14, 15 and 16, may be employed to permit 90 the turning of the spring band sections in their holes in the pads for varying the tensions of the bands.

The leg bands, 5 and 6, are preferably 95 connected to the waist band, 1, by means of detachable, swivel connectors. For this purpose the well known form of snap swivel shown at 7 and 8, Fig. 1, and in full size detail in Fig. 11 may be employed. As 100 shown in the drawings it is composed of a swivel such as that shown at 14, and a snap hook, 17, which latter is hooked through a single loop, 18, of the band, 1. It will be understood that any suitable form of connector may be used. 105

While I prefer to make my elastic bands of the helical wire spring construction shown and described, a modification of this construction is shown in Figs. 4 and 5. In this construction helical wire springs are 110 used for the leg bands, as shown at 19; for the ends of the waist bands as shown at 20; and for the connection between the pads as shown at 21; but the body contacting portion, 22, of the waist band is made of non- 115 elastic webbing which may be preferred by those whose skin is over sensitive. The advantage of the metal, wire spring 1 is that it is waterproof and the truss may be worn in the bath or while swimming and offer no 120 discomfort when the clothes are afterwards put on over it.

In Fig. 14 a modified form of swivel or turn-buckle is shown in which the body, 23, is elongated and has a swivel eye, 23^a, in one 125 end and a hole, 24, in the other end adapted to receive the wire of the spring, 25, in the same manner that the hole, 12, in the face of the pad receives it. This swivel construction may be employed for adjusting the 130

length and consequently the tension of the band without screwing the spring into or out of the pad. In some instances it may be convenient to use this form of swivel, as for instance, in the middle of the back of the waist band shown at 1 in Fig. 1.

For stout persons or in severe cases of hernia it may be desirable to use larger and stronger springs than those shown and described herein, or, two or more parallel springs may be used as shown in Fig. 15, in which two springs, 26 and 27, compose the waist band and are shown separately screwed into the pad, 28, in the same manner that a single spring would be screwed into it.

The main portion of the waist band may be detachably secured to the members which are secured to the pads by means of snap 20 swivels as shown at 29 and 30, Figs. 4 and 5.

As shown in Figs. 1 and 2, the pads 2 and 3, are pressed against the body in a direction along the axes of the pads. In Fig. 3 the portion, 4^a, of the waist band is shown 25 screwed into a hole in the pad, 3, near the center of the back of the pad so that the tension of the spring, 4^a, tends to tip the pad and cause it to exert its pressure at an angle to its axis, as clearly shown in Fig. 3.

30 It will be apparent to those skilled in the art that by varying the points of attachment of the waist and leg bands to the pads, the latter may be more conveniently located for position and caused to exert their pressures 35 in any direction desired. For this purpose a plurality of holes, 12, is preferably provided in the pads.

For supporting hernia it is sometimes found desirable to use elongated pads such 40 as are shown in Figs. 12 and 13. It is obvious that my invention accommodates itself readily to such conditions.

It will be apparent to those skilled in the art that various combinations of bands and 45 connecting swivels, both permanent and detachable, may be made without departing from the scope of my invention. It will also be apparent that the waist band may be made in any convenient number of sections and that the sections may include both 50 elastic and non-elastic materials and that protective pads may be employed between the spring and the body of the wearer where desired.

55 The pads, helical springs and the connections, swivels and snap swivels, may be nickel plated or otherwise protected against corrosion.

It will be observed that the surplus ends 60 of the helical springs which are screwed into the pads are completely inclosed by the pads and cannot injure or annoy the wearer. I have found that several inches of length of 65 all of the bands that are connected to a pad can be readily screwed into the hollow in-

terior of the pad. The same lengths of bands can therefore be adjusted to fit a wide range of body proportions. This feature facilitates the manufacture as well as the fitting of the trusses.

70

I claim:—

1. In an all metal abdominal truss, a pad, a helical wire spring secured to said pad and adapted to form a waist band.

2. In an all metal abdominal truss, a hollow pad having a wire receiving aperture and a helical wire spring band having the convolutions of one free end screwed into said aperture and its other end secured to a swivel connector included in said band. 75

3. In an all metal abdominal truss, a pad, a helical wire spring secured to said pad and adapted to form a waist band, and a helical wire spring leg band also secured to said pad and adapted to extend downwardly 80 therefrom under the torso of the wearer and be attached to said waist band at the back.

4. In an abdominal truss, a pad, and a band adapted to hold the pad to the body of the wearer of the truss, said band including a helical wire spring adjustably secured to said pad by having its free end convolutions screwed into an aperture in said pad. 85

5. In an abdominal truss, a pad, a band 90 adapted to hold the pad to the body of the wearer of the truss, said band comprising a plurality of sections one of them including a helical wire spring secured to said pad by having its free end convolutions screwed into 100 an aperture in said pad, and a swivel connection between sections of said band.

6. In an abdominal truss two hollow pads each having a plurality of wire receiving 105 apertures, a waist band adapted to hold said pads to the body of the wearer of the truss, said band including two lengths of helical, wire spring joined end to end by a swivel connector whereby said spring lengths may turn about their axes independently of each other, one end of said waist band being adjustably connected to one of said pads by having its free end convolutions screwed into an aperture in said pad, and the other end of 110 said waist band being connected to the other of said pads, and adjustable means connecting said pads to complete said waist band. 115

7. In an abdominal truss, a pad and a band secured thereto adapted to secure the truss to the body of the wearer, said band including a turn-buckle section having a wire receiving aperture and a section composed of a helical, wire spring, said spring being adjustably connected to said turn-buckle section by having one end of its helical convolutions screwed through said aperture. 120

8. In an abdominal truss a hollow pad having a wire receiving aperture in its wall, a waist band having two sections connected by a swivel joint, one of said sections com- 125

130

prising a helical, wire spring having its free end adjustably connected to said pad by being threaded through said aperture, the other end of said waist band being connected to said pad.

9. In an abdominal truss, a hollow pad having a plurality of wire receiving apertures, a waist band comprising a plurality

of sections of helical, wire spring connected end to end, a swivel joint forming one of said connections, the free ends of said waist band being adjustably secured to said pad by being threaded through respective ones of said apertures.

JAMES O. KING.
